UNITED STATES PATENT OFFICE.

WALTER EDWARD PEHL, OF AUSTIN, TEXAS.

COTTON-PICKER.

1,160,446.

Specification of Letters Patent. Patented Nov. 16, 1915.

Application filed June 16, 1915. Serial No. 34,493.

To all whom it may concern:

Be it known that I, WALTER E. PEHL, a citizen of the United States, residing at Austin, in the county of Travis and State of Texas, have invented certain new and useful Improvements in Cotton-Pickers, of which the following is a specification, reference being had to the accompanying drawings.

10 This invention relates to certain improvements in cotton pickers; and it is an object of my invention to provide a device of this general character having novel and improved means whereby the cotton is collected independently of the bolls.

15 It is also an object of my invention to provide a device of this general character having novel and improved means whereby a twisting action is given to the cotton through the medium of a rotatable member and whereby said cotton, after being extracted from within the boll, is caused to be collected substantially an automatic manner.

20 Furthermore, it is an object of my invention to provide a device of this general character adapted to coat with the opposite sides of a row of plants and wherein the same is capable of convenient lateral adjustment in order to compensate the same for use in connection with rows of varying widths.

25 The invention consists in the details of construction and in the combination and arrangement of the several parts of my improved cotton picker whereby certain important advantages are attained and the device is rendered simpler, less expensive and otherwise more convenient and advantageous for use, all as will be hereinafter more fully set forth.

30 The novel features of the invention will be carefully defined in the appended claims.

In order that my invention may be the better understood, I will now proceed to describe the same with reference to the accompanying drawings, wherein—

35 Figure 1 is a view in top plan, with the seat structure omitted, of a cotton picker constructed in accordance with an embodiment of my invention; Fig. 2 is a longitudinal vertical sectional view taken through my device as herein embodied, with the seat structure shown in elevation; Fig. 3 is a view partly in rear elevation and partly in section, 40 of my improved harvester as herein embodied; Fig. 4 is a view, partly in elevation and

partly in section, of the forward arch of my device as herein embodied and illustrating certain details of the steering mechanism herein included; Fig. 5 is an enlarged fragmentary vertical sectional view taken through one of the collecting cylinders forming part of my invention as herein set forth, certain of the parts coacting therewith being shown in elevation; Fig. 6 is a sectional view taken substantially on the line 6—6 of Fig. 5; Fig. 7 is a sectional view taken substantially on the line 7—7 of Fig. 6; and Fig. 8 is an enlarged fragmentary sectional view illustrating a clutch mechanism embodied herein.

45 As disclosed in the accompanying drawings, 1 and 2 denote, respectively, the front and rear arches of my improved machine as herein set forth, the rear arch 2 being provided with the outwardly disposed trunnions 3 on which are mounted the supporting wheels 4. Each of the arches 1 and 2 comprises duplicate sections whereby the same may be readily and conveniently adjusted to compensate the device for use in connection with rows of varying widths and, as herein set forth, the adjacent extremities of the front or forward arch 1 are telescopically engaged within the sleeve 5 and maintained in their predetermined adjustments relatively to the sleeve through the medium of the binding members 6, herein set forth as conventional set screws, threaded through the sleeve and engaging the extremities of 50 the sections.

55 The rear arch 2 has its adjacent extremities telescopically engaged with the sleeve 7, said sleeve being secured to one of the sections through the medium of the conventional clamping member 8 while the inner extremity of the adjacent section of the arch has adjustably secured thereto through the medium of the conventional clamping member 9, a sleeve 10 positioned within the 55 recessed portion 11 of the sleeve 7 whereby it will be observed that the sections of the rear arch 2 are capable of limited relative movement. This arrangement is believed to be clearly disclosed in Figs. 1 and 3 of the 60 accompanying drawings.

65 The vertical members of the forward arch 1 are tubular and have disposed therethrough rods 12 capable of axial rotation, the lower extremities of said rods below the 65 vertical members of the arch being disposed outwardly to afford the trunnions 14 on

which are mounted the supporting and steering wheels 15. The rods 12 extend above the arch and to the upper extremities thereof are suitably affixed the parallel rock arms 16 tied or connected by the link 17 whereby said rods 12 may be caused to rotate in unison and in the same general direction. One of the arms 16 is provided with a lateral extension 18 having pivotally secured thereto the rearwardly disposed bar 19 suitably engaged with the lever 20 carried by one of the frames F positioned in close proximity to the seat structure S, herein set forth as being operatively engaged with the sleeve 7, hereinbefore referred to. As is believed to be self-evident, upon requisite rocking movement being imparted to the lever 20, the rods 12 may be rotated in such a manner as to control the direction of travel of the device. It may also be well to state that the lever 20 is provided with a conventional latch mechanism 21 coacting with a rack 22 also carried by the frame F. As herein embodied, the frame F is interposed between the corresponding vertical members of the arches 1 and 2 and is substantially rectangular in form with its transverse diameter vertically disposed and the forward end of the frame F is provided with an extension 23 pivotally engaged, as at 24, about a vertical axis with the sleeve or collar 25 loosely mounted upon a vertical member of the forward arch 1 and maintained in a predetermined position upon said vertical member through the medium of the collars 26 in a manner which is believed to be fully disclosed in the accompanying drawings. The opposite or rear end of the frame F is provided with an extension 27 loosely engaged with a vertical member of the rear arch 2 and maintained in its adjustment thereon in an obvious manner through the medium of the collars 28.

At predetermined intervals longitudinally thereof, the frame F is provided with the vertically disposed shafts 29, to each of which is suitably affixed, as indicated at 30, a tubular drum or cylinder 31.

Projecting radially from the cylinder 31 are the vertical series of tubular bearings 32 disposed in predetermined proximity one to the other. In the accompanying drawings, I have illustrated four of these series but I wish to be particularly understood that these series may be of a greater number if the requirements of practice should so necessitate.

Rotatably supported by each of the bearings 32 is a picker stem 33 capable of axial rotation and having a flattened portion 34 projecting forwardly of the bearing 32 a predetermined distance and terminating in the reversely directed teeth or extensions 35. The teeth or extensions 35 are adapted to engage the cotton when in the boll and the

rotary movement of the picker stem results in such twist being imparted to the cotton as to withdraw or extract the same from within the boll.

As herein embodied, the picker stem 33 extends inwardly of the cylinder 32 and to the inner extremity thereof is affixed a gear 36 and the gears 36 of each series are in mesh so that the same may be caused to rotate in unison from a common source of power. 70

In the present embodiment of my invention, the gear 36 of the uppermost picker stem 33 of each series is in mesh with the stationary annular rack member 37, herein set forth as operatively supported by the upper bar 38 of the frame F and positioned within the cylinder 31 whereby the rotation of the cylinder 31 results in the desired axial rotation being imparted to the picker stems 33. Each of the shafts 29 extends above the upper bar 38 of the frame F and is in operative engagement, as indicated at 39, with the shaft 40 disposed longitudinally of the bar 38 and in chain connection, as indicated at 41, with the stub shaft 42, said shaft 42 being in operative engagement, as at 43, with the vertical shaft 44. The lower extremity of the shaft 44 is operatively engaged, as at 45, with the wheel 4 whereby it will be readily perceived that upon axial 85 rotation being imparted to the wheel 4, the shaft 40 and its coacting members will be caused to rotate. 90

In the present embodiment of my invention, the chain 41 is directed around a sprocket 46 loosely mounted upon the shaft 40 and in close proximity to a clutch member 47. Carried by the clutch member 47 are endwise movable latches 48 adapted to extend within the openings 49 produced in the sprocket 46 and maintained in such engagement under the influence of the expandable members 50, as is believed to be clearly shown in detail Fig. 8. The inner extremities of the latch members 48 are angularly disposed, as indicated at 51, and when such latch members 48 are in operative engagement with the sprocket 46, are disposed within the recesses 52. It will be readily understood that when the latch members 48 are withdrawn from engagement with the sprocket 46, it is only necessary to sufficiently rotate said latches to cause the angular extremities 51 to overlie the adjacent end face of the clutch member 47 to maintain said latches out of engagement with the sprocket 46 whereupon said sprocket will run idle. 110

Mounted for sliding movement upon each of the bearings 32 is a cylinder 53, the outer end of which being open and provided with the diametrically opposed flat springs 54 bearing against opposed faces of the flat portion 34 of the picker stem 33. The inner or closed end of the cylinder 53 is adapted to be engaged by the fork 55 projecting 115

laterally from the vertically disposed shaft 56 rotatably supported by the frame F and having its upper extremity terminating in the angular extension 57. As the cylinder 53 rotates, the extension 57 will come into contact with the trip 58 carried by the upper bar 38 of the frame F with the result that the cylinder 53 will be forced outwardly so that the members 54 will strip the picker 10 stem 33 of the cotton carried thereby. It is to be understood that the springs or members 54 possess sufficient resiliency as to offer no obstruction to the rotation of the picker stems 33. After the extension 57 has passed 15 the trip 58, the cylinder 53 is moved inwardly to its normal position under the influence of the expansible member 59, herein disclosed as a conventional coil spring, surrounding the bearing 32 and interposed 20 between the inner end of the cylinder 53 and a projection 60 carried by the bearing 32 adjacent its outer extremity. Upon being released from the picker stem 33, the cotton falls upon the endless apron 61 operatively 25 engaged with the parallel shafts 62 mounted in the lateral end extensions 63 carried by the frame F and disposed outwardly therefrom. The apron 61 delivers upon the substantially vertically disposed endless apron 30 64 operatively engaged with the shafts 65 also supported by the end extensions 63, said apron 64 being adapted to discharge within the collecting member or trough 66 supported by the extension 63 and in close proximity to the upper shaft 65. The opposite extremities of the upper shafts 65 are provided with the sprockets 67 around which are disposed the chains 68 operatively engaged with the shafts 40. The opposite extremities of the lower shaft 65 are also provided with the sprockets 69 around which are disposed the chains 70 also operatively engaged with the shafts 40. The opposite extremities of the lower shaft 65 are also 40 operatively engaged, as indicated at 71, with one of the shafts 62.

While any draft mechanism may be employed in connection with my improved device as herein disclosed, I prefer to employ 50 the arrangement disclosed in the accompanying drawings wherein the sleeve 5 has projecting forwardly therefrom at substantially its longitudinal center the arm 72 to the outer extremity of which is pivotally engaged the central portion of the transversely disposed arm 73. Depending from the opposite extremities of the arm 73 and in pivotal engagement therewith are the beams 74, the lower extremities of which being pivotally 55 engaged with the arms 75 projecting forwardly from the lower extremities of the vertical members of the forward arch 1 and

pivotal engaged therewith, as indicated at 76, for movement about a vertical axis. It is to be observed that the arms 17 and 73 are 65 telescopically engaged with sleeves, similar to the arrangement of the arch member 1 in the sleeve 5. The beams 74 are provided with the longitudinally disposed spaced openings 76 to afford means whereby a conventional 70 draft rigging 77 may be coupled thereto. It is thought to be clearly apparent that the draft mechanism as herein disclosed effectively serves as an evener.

From the foregoing description, it is 75 thought to be obvious that a cotton picker constructed in accordance with my invention is of an extremely simple and comparatively inexpensive nature and is particularly well adapted for use by reason of the convenience 80 and facility with which it may be assembled, and it will also be obvious that my invention is susceptible of some change and modification without material departure from the principles and spirit thereof and for this 85 reason I do not wish to be understood as limiting myself to the precise arrangement and formation of the several parts herein shown in carrying out my invention in practice. 90

I claim:

1. A machine of the character described comprising a frame, a rotatable picker stem carried thereby, a cylinder surrounding the picker stem and mounted for movement longitudinally thereof, the outer end of said cylinder being open and provided with flat springs bearing against the picker stem, spring means within the cylinder for normally maintaining the cylinder in a position 95 inwardly of the picker stem, and trip controlled means engageable with the inner end of the cylinder for imparting outward movement to the cylinder.

2. A machine of the character described 105 including a rotatable member, a bearing radiating from said member, a picker stem rotatably supported by said bearing and projecting therebeyond, a cylinder slidably mounted upon the bearing and provided 110 with outwardly disposed flat springs engageable with the picker stem, a trip operated shaft carried by the rotatable member engageable with the cylinder for imparting outward movement thereto, and an expansible member coacting with the bearing and the cylinder for imparting movement to the cylinder in an opposite direction. 115

In testimony whereof I hereunto affix my signature in the presence of two witnesses. 120
WALTER EDWARD PEHL.
